(57) **CLAIM**

The ornamental design for a table leveler, as shown and described.

DESCRIPTION

FIG. 1 is a top perspective view of a table leveler incorporating the new design.

FIG. 2 is an alternate top perspective view of a table leveler incorporating the new design.

FIG. 3 is a bottom perspective view of a table leveler incorporating the new design.

FIG. 4 is an alternate bottom perspective view of a table leveler incorporating the new design.

FIG. 5 is a top plan view of a table leveler incorporating the new design.

FIG. 6 is a bottom plan view of a table leveler incorporating the new design.

FIG. 7 is a front elevational view of a table leveler incorporating the new design.

FIG. 8 is a rear elevational view of a table leveler incorporating the new design.

FIG. 9 is a side elevational view of a table leveler incorporating the new design; and,

FIG. 10 is an opposite side elevational view of a table leveler incorporating the new design.

The broken lines in the drawings illustrate portions of the table leveler which form no part of the claimed design.
